GIUSEPPE BORGATTA, OF GENOA, ITALY.

WAVE-DRIVEN PUMPING GEAR.

Application filed April 25, 1927. Serial No. 186,299.

This invention relates to wave-driven pumping gear and has for an object to provide a device which is very simple, cheap in its construction and mounting and effective 5 for use in utilizing the wave movements of bodies of water, such as seas or lakes, for raising water, and which will avoid all unnecessary strains due to high waves.

Devices employing the reciprocating movement of the waves as a power source are known, such contrivances being generally of the kind in which a floating body is connected either directly, or through suitable gearing, to a plunger element of a pump or the like, 10 in order to raise some of the lake or sea water into suitable storage tanks or the like, arranged at a suitable height above the water level. But all the contrivances as hitherto devised present mainly the inconvenience that 15 the floating body and the reciprocating member of the pump are connected in such a manner that for each movement or strain exerted on the former there is a correspondingly great movement or strain upon the pumping element. Thus the rate of flow or efficiency below the limits of displacement of the reciprocating element of the pump is very small, but just 20 beyond said limits it is transformed into a force which is transmitted to the pumping gear and driving connections in the form of serious strains or shocks, which, especially in storms or heavy seas, are very detrimental 25 to the whole of the pumping gear and supporting structures.

The object of the present invention is to provide a device which will overcome the above drawbacks, as the working stroke of the plunger element will be independent, 30 within wide limits, of the possible reciprocal displacements of the floating body driving the pumping gear, which latter will be always immune from unnecessary strains or shocks caused by the floating body rising above or falling below the useful limits of the working 35 stroke of the piston-like element, and which will have, above certain limits of height of wave a substantially constant efficiency.

With these and other objects in view, the 40 present invention consists in the special construction of the pumping gear and in the special arrangement of parts connected there-

with, to be fully described hereinafter with respect to one embodiment shown in the accompanying drawing.

55

In the drawing:

Figure 1 is a side view of an example of construction of a device embodying the invention;

Figures 2 and 3 are horizontal sectional views respectively on lines II-II and III-III of Figure 1;

Figure 4 is a vertical section through the pump in enlarged scale;

Figure 5 is a partial sectional view on line V-V of Figure 4.

On the bottom of the sea or lake is mounted a suitable vertical supporting structure, preferably made of upright angle bars 1, such structure supporting at suitable heights a 70 number of platforms 3, 4, 5 or the like, which serve to guide and support the controlling member of the system. In the example shown between the two platforms 3 and 4 and suitably fastened thereto are mounted two parallel plates 6, 6' suitably leveled and smoothed in their inner opposed surfaces, the said plates combining to constitute the pump casting. Between the said two plates are arranged two movable members 7, 7' formed 75 of two T-shaped plates, the leg of the T being turned outwardly, and the said elements being bent at their middle portions so as to assume a V-shape with the wide side of the V opening to the exterior.

85

Each of the said members bears at the vertex of the V-shaped element a hinge eye 8, 8' in which a pivot is threaded, fastened to the plates 6, 6', the other end of the lower hinged arm being also formed with a hinge-eye 9, 9' 90 by means of which it is hinged to another movable element 10, 10' of like section to the former but straight. These movable members 10, 10' are of a length that is equal to that of the lower arms of the members 7, 7' 95 and are hinged at their lower ends 11, 11' to a transverse member 12 which is also movable so that the lower arms of the members 10, 10' and the piece 12 form an articulated polygon, which is symmetrical with regard 100 to the vertical axis of the system. A fixed transverse member 13 closes the space between hinges 8, 8' and members 7, 7', so that by arranging suitable packings 14 on all the

free sides of the said polygon, so as to allow the said packings to remain in contact with the smoothed inner faces of plates 6, 6', a closed chamber will be formed between the 5 said polygonal element and the said plates, the capacity of which will vary according to the positions of members 7, 7' pivoting on hinge joints 8, 8'. The chamber will have a minimum capacity when the sides of the 10 polygon are parallel (the position shown in dotted lines in Figure 4) and a maximum corresponding to the vertical position of the upper arms of members 7, 7' (shown in full lines of Figure 4) when the said arms come 15 into contact with the fixed stops 15.

These periodical variations of capacity correspond respectively to a compression stroke forcing liquid through valve 16 mounted on one of the plates 6, 6' in a suitable position, 20 and to a suction stroke for allowing water to pass through a suitable valve 17 mounted on the other plate. The system therefore will be able to work as a pump, without lower capacity limits, but limited at the maximum 25 working capacity per stroke by the difference between the maximum and minimum deformations of the polygonal chamber.

In order to govern the said pivotal movement of the members 7, 7', two sliding trolleys 18, 18' are provided, each trolley being formed by a stirrup member 19 including between its inturned wings the plates 6, 6'. The outer edges of the said wings are bent at right angles and are thus at right angles to the plates 6, 6'. On each of the said bent edges presses a pair of horizontal springs 22 abutting at their ends against the wing of an angle plate which is parallel and adjacent to the stirrup wing 19. This bent wing of 30 the angle plate has a pivot threaded through a horizontal slot out in the wing of the piece 19, there being mounted on the inner end of the pivot a suitable roller which is allowed to roll along one of the vertical guides 20, 20' outwardly fastened on the borders of plates 6, 6'. Each stirrup member 19 is consequently forced by the pressure of two pairs of springs 22 against the inturned border flanges of the stirrup 19 and is guided at the 35 same time along the guides 20, 20' on four rollers. Each stirrup 19 bears a forked extension extending centrally between plates 6, 6'. Between the two arms of this extension is mounted a suitable grooved roller 21 on a suitable pin threaded through the said arms. The roller 21 bears with its groove against the wing of the associated T-shaped member. Thus the pressure transmitted by springs 22 abutting against their respective rollers to 40 the member 19 acts finally on the wing of the T-shaped member through the grooved roller 21. Each trolley 18, 18' thus formed is also connected by means of sleeves 23 to vertical bars 24, 24'. These two bars after having 45 passed through suitable guides 25, 25' in the

platform 4 are connected together by a yoke 26 to a single central bar 27 threaded through a guide sleeve in the platform 5, and is attached at the water level to a suitable floating body 28, which is guided in its vertical movement by means of suitable guide columns 29 and limited in its upward movement by a suitable platform stop or the like 30. Suitable rods 31 connect the platforms 30 and 5, thus strengthening the structures. 70

From the foregoing description the working of the above device will be clear. When the floating body descends in a wave trough the trolleys 18, 18' travel down the lower portions of arms 7, 7' forcing them together by 80 making them pivot around around the pivots 8, 8' and consequently reducing the capacity of the chamber between the deformable polygon; and when the floating body rises again, the said trolleys, having left the lower arm 85 portions, move up along the upper arms of members 7, 7' thus imparting to them a rotation in a contrary direction until they become parallel to one another, thus increasing the 90 capacity of the polygon. In this manner the working and suction strokes are effected.

Every movement of the floating body beyond the maximum and minimum limits of the deformation of the polygon has no effect on it; the floating body is allowed to rise and fall beyond the useful working limits independently of the working stroke of the pump and only within the constructional limits of the sliding surfaces of the structure, which surfaces may be as great as possible, independently of the working capacity per full stroke, which is only dependent upon the characteristics of the pump. 95

It is apparent that many constructional variations of the example described and shown are possible. This example is to be considered only as explanatory. In practice the elements which remain in contact with the water will be suitably protected from rust and incrustations. Moreover the pump 105 as well as the floating body system will admit also of many constructional variations within the limits of the invention and the scope of the appended claims.

Claims:

1. In wave-driven pumping gear, a pumping element including two fixed plates parallel to one another and having smooth inner opposed faces, substantially V-shaped elements mounted between said plates on pivots 120 extending transversely thereof, other movable elements hinged at their upper ends to the lower ends of said V-shaped elements, means hingedly connecting the lower ends of said other elements to constitute a parallelogram with the lower ends of said V-shaped elements, packings between the movable elements and the fixed plates attached to the former, suction and pressure valves on the fixed plates, a floating body, and means at- 130

tached to said floating body and actuated by its movements to operate said V-shaped and other elements.

2. In wave-driven pumping gear, a pumping element including two fixed plates parallel to one another and having smooth inner opposed faces, substantially V-shaped elements mounted between said plates on pivots extending transversely thereof, other movable elements hinged at their upper ends to the lower ends of said V-shaped elements, means hingedly connecting the lower ends of said other elements to constitute a parallelogram with the lower ends of said V-shaped elements, packings between the movable elements and the fixed plates attached to the former, suction and pressure valves on the fixed plates, a floating body, guide rails parallel to the pumping element, control slides movable along said rails and including rollers adapted to bear against said V-shaped elements, and means connecting said floating body to said slides.

3. A wave-driven pumping gear comprising a pumping device including a chamber having expansible and contractible side walls, slides having rollers engageable with said side walls to operate said pumping device, and a floating body connected with said slides for operating the same to actuate said pumping device in accordance with the movements of said floating body.

4. A wave-driven pumping gear in accordance with claim 3, in which said chamber includes two parallel fixed plates and in which portions of said expansible and contractible side walls are formed of V-shaped members which are engaged by said rollers, the remaining portions of said side walls being connected to the V-shaped members, an upper fixed plate secured to the first named plates and forming a closure for the upper end of said chamber, a vertically slidable plate forming a lower closure for said chamber, suction and pressure valves arranged on said first named fixed plates, said V-shaped elements being T-shaped in cross-section with the two wings thereof tightly fitted against said first named fixed plates, and springs exerting a pressure upon said rollers to engage the same with said V-shaped elements during the operation of said rollers by said floating body.

chamber, a vertically slidable plate forming a lower closure for said chamber, and suction and pressure valves arranged on said first 45 named fixed plates.

5. A wave-driven pumping gear in accordance with claim 3, in which said chamber includes two parallel fixed plates and in which portions of said expansible and contractible side walls are formed of V-shaped members which are engaged by said rollers, the remaining portions of said side walls being connected to the V-shaped members, an upper fixed plate secured to the first named 55 plates and forming a closure for the upper end of said chamber, a vertically slidable plate forming a lower closure for said chamber, suction and pressure valves arranged on said first named fixed plates, and platforms 60 limiting the movements of said floating body.

6. A wave-driven pumping gear in accordance with claim 3, in which said chamber includes two parallel fixed plates and in which portions of said expansible and contractible 65 side walls are formed of V-shaped members which are engaged by said rollers, the remaining portions of said side walls being connected to the V-shaped members, an upper fixed plate secured to the first named plates 70 and forming a closure for the upper end of said chamber, a vertically slidable plate forming a lower closure for said chamber, suction and pressure valves arranged on said first named fixed plates, said V-shaped elements being T-shaped in cross-section with the two wings thereof tightly fitted against said first named fixed plates, and springs 75 exerting a pressure upon said rollers to engage the same with said V-shaped elements 80 during the operation of said rollers by said floating body.

In witness whereof I affix my signature.
